UNITED STATES PATENT OFFICE.

CHIKAZO WATANABE, OF LOS ANGELES, CALIFORNIA.

SHOE SHIELD.

Application filed January 5, 1928. Serial No. 244,658.

This invention relates to a device for protecting a shoe, and the objects of the invention are to provide a protecting pad, which is adapted to be secured to the rear portion 5 of a shoe, and to be disposed on the inner side of the shoe, to protect the shoe from unusual wear, and to protect the foot of the wearer; the device being particularly adapted to protect the upper edge of the shoe; to facilitate 10 the putting on and taking off of the shoe, to prevent chafing, and to protect the stockings of the wearer.

Another object is to provide a device of this character which will be maintained in position by the foot of the wearer when applied to the shoe.

The further advantages of this device are, that the same can be instantaneously attached or removed, or if preferred, may be secured 20 permanently in position by nailing to the shoe sole, that the device does not require alteration of the shoe, and that the device affords protection both to the shoe and to the foot of the wearer.

25 My improved shoe shield, consists of a plate of celluloid material, and a strip of aluminum sheet metal secured thereto and adapted to be positioned against the inner side of the shoe; the plate having its upper edge turned to extend over the upper edge of the shoe, and the metal strip having a toothed upper edge to engage with the shoe to prevent displacement when the shoe is applied to and removed from the foot of the wearer.

35 In the drawings, Figure 1 is a front view of my improved shoe shield. Fig. 2 is side elevation of the device. Fig. 3 is a top plan view of the device. Fig. 4 is a fragmentary and sectional view of a shoe, showing the 40 shield applied thereto. Fig. 5 is a plan of the celluloid blank before folding and shaping the same. Fig. 6 is a rear elevation of the device, showing the same before bending the inner tip.

45 Referring to the drawings, the main portion 10, consists of a plate formed from celluloid material, and has the inner tip 11,

adapted to extend over the inner heel portion 12, of a shoe 13. The upper edge 14, of plate 10, is turned to form a flange portion 50 15, adapted to extend over the upper edge 16, of the shoe. A strip 17, of aluminum sheet metal, is secured to the plate 10, and both the strip 17 and plate 10, are adapted to be disposed on the inner side of the shoe. The upper end 18, of strip 17, is provided with teeth 19, adapted to press into the inner side of the shoe, thereby preventing the device from being displaced when the shoe is applied to or removed from the foot of the wearer. The 60 eyelets 20, serve to hold the strip 17 and plate 10, together. If desired to secure the device permanently in position, a nail (not shown) may be inserted in the eyelet in the inner tip 11, and driven into the shoe sole.

65 This device, as illustrated and described, serves to efficiently protect the shoe, to facilitate the manipulation of the shoe relative to the foot of the wearer, to keep the feet dry, and to prevent the real cause of illness—cold 70 or damp feet.

What is claimed is:

1. A shoe shield, comprising a plate of celluloid material having a portion arranged to extend within a shoe, a strip of aluminum 75 metal secured thereto and to the portion thereof extending within the shoe, and a flange portion on said plate adapted to extend over the upper edge of a shoe.

2. A shoe shield, comprising a plate of celluloid material to be positioned against the inner side of a shoe, an inner tip portion integral therewith, and a metallic strip reinforcing the plate and tip.

3. A shoe shield, comprising a plate of celluloid material to be positioned against the inner side of the shoe, a flange portion adapted to extend over the upper edge of the shoe, an inner tip portion adapted to extend beneath the foot of the wearer, and a metallic 90 strip reinforcing the plate and tip.

In testimony whereof, I hereunto affix my signature.

CHIKAZO WATANABE.
